UNITED STATES PATENT OFFICE.

AUGUST LARGILLIERE, OF SODA SPRINGS, IDAHO.

DIRIGIBLE SLEIGH.

Application filed March 21, 1925. Serial No. 17,207.

To all whom it may concern:

Be it known that I, AUGUST LARGILLIERE, a citizen of the United States, residing at Soda Springs, in the county of Caribou and State of Idaho, have invented certain new and useful Improvements in Dirigible Sleighs, of which the following is a specification.

My invention relates to self propelled sleighs, and has for its object to provide a sleigh which is drawn by a motor driven propeller secured on the front end of the sleigh and which propeller is pivoted to the body of the sleigh by a manually controlled universal pivot, in order that the sleigh may be guided and directed in its travel. A further object is to provide a braking device by which the sleigh may be also directed and retarded in its travel.

These objects I accomplish with the apparatus illustrated in the accompanying drawings in which similar letters and numerals of reference indicate like parts throughout the several views, and as described in the specification forming a part of this application and pointed out in the appended claim.

In the drawings in which I have shown the best and most substantial embodiment of my invention, Figure 1 is a side elevation of the apparatus. Figure 2 is a front elevation of the apparatus, parts cut away. Figure 3 is a longitudinal section on line 3-3 of Figure 1, but not cutting the engines and propeller.

The invention consists of the new and novel combination, arrangement and construction of the several parts of the apparatus, and as shown a pair of spaced apart runners A support the body and mechanism of the apparatus. A frame B is secured on said runners and held above them by the spiral springs C which are held under slight compression by the bolts 18 and knee braces of the sleigh, and which bolts 18 hold said springs from undue expansion and the consequent injury to the braking elements of the apparatus. The body D, of the sleigh is shown as enclosed and with seats S for the operator, and with doors of ingress and egress. An internal combustion engine E, is mounted in front of, and secured to the upper portion of the body of the sleigh, and braced laterally by the braces 1. A base plate 2 is provided, to which the upper ends of said lateral braces

1 are secured, and through which the pivot rod 3 is journaled. The said pivot rod 3 extends downwardly to near the said frame B, and on its lower end is secured a segment 60 gear 4, whose teeth mesh with the teeth of a spur gear 5. The said spur gear 5 is secured on a shaft 6 having a universal joint 7 therein. A hand or steering wheel 8 is secured on the said shaft 6 by which 65 the said shaft is rotated. The base plate 10 of the engine E is secured on the upper end of said pivot rod 3 and as said pivot rod is partially rotated the engine E is turned, together with the propeller P, 70 which is secured on the front of said engine. A foot pedal 11 is fastened to one arm of a rocking shaft 12, and the other arm of said shaft 12 is pivoted to the brake shoe 13, by the link rod 14. The said brake 75 shoe 13 is carried on a transverse pipe or rod 15, that in turn is secured on the underside of said body, and each side of the apparatus has a brake shoe. Side springs 16 are provided and which are each secured at 80 one end thereof to the adjacent runner A and the rear end is slidable on said runner.

Having described the invention I will now describe its operation. Having started the engine the apparatus is drawn forward, and 85 its direction may be changed by partially turning the engine on the base plate 2. This may be done by partially rotating the pivot rod 3 by means of the gears 5 and 7. If the apparatus is moving over the snow by 90 the pull of the propeller P, the direction may be controlled by the foot of the operator, by pushing down on one of the said foot pedals 11, which rotates the rocking shaft 12 connected therewith, whereby the 95 lower end of the brake shoe is made to engage the ice, or snow over which the apparatus is sliding and the apparatus will be drawn in that direction. Similar braking elements are provided on both sides of 100 the apparatus, that is, another foot pedal, rocking shaft, link rod and brake shoe are similarly mounted on the other side and runner of the apparatus. I provide a spring 17 for each of the brake shoes, having one 105 end fastened to the frame B and its other end to the upper portion of the shoe, to normally hold them out of engagement. When I desire to stop, or to slow down 110 when gliding down an incline I apply both brakes, by pushing down of the foot pedals 11, as well as to stop the engine.

2
Having thus described my invention and its operation I desire to secure by Letters Patent and claim:—

A dirigible sleigh comprising a pair of 5 runners; a frame secured thereon; springs between said runners and said frame; an enclosed body secured on said frame; an engine base secured to the front of said body and supported by said frame; an engine pivoted on said base; a depending pivot rod to whose upper end said engine is secured, and to whose lower end a segment 10 is fastened; a steering wheel

having a depending rod; a spur gear secured on and rotatable with said steering 15 rod, with its teeth meshing with the teeth of said segment gear; a propeller secured on and operable by said engine; a brake shoe on each side of said frame adapted to engage with the earth; and means to manually 20 operate each of said brake shoes independently of the other.

In testimony whereof I have affixed my signature.

AUGUST LARGILLIERE.
